UNITED STATES PATENT OFFICE.

WILLARD A. VAN BRUNT, OF HORICON, WISCONSIN, ASSIGNOR TO THE VAN BRUNT & DAVIS COMPANY, OF SAME PLACE.

SEEDING-MACHINE.

SPECIFICATION forming part of Letters Patent No. 425,274, dated April 8, 1890.

Application filed August 16, 1889. Serial No. 320,935. (No model.)

To all whom it may concern:

Be it known that I, WILLARD A. VAN BRUNT, of Horicon, in the county of Dodge and State of Wisconsin, have invented certain new and useful Improvements in Seeding-Machines; and I do hereby declare the following to be a full, clear, and exact description of the invention, such as will enable others skilled in the art to which it appertains to make and use the same.

My invention relates to an improvement in seeding-machines, the object being to provide a light-running machine which may be quickly transformed into a drill-seeder, a broadcast-seeder, or a cultivator, according to choice.

A further object is to furnish a simple and durable machine having few parts capable of easy adjustment.

A still further object is to provide a machine which may be easily taken apart for shipping and have its various parts renewed in case of breakage or undue wear, and in so doing to produce a machine which may be placed on the market at a comparatively slight cost.

With these ends in view my invention consists in certain novel features of construction and combination of parts, as will be herein-after fully described, and pointed out in the claims.

In the accompanying drawings, Figure 1 is a side elevation. Fig. 2 is a plan view. Fig. 3 is a sectional view through the seed-hopper. Fig. 3^a is an end view of the device. Figs. 4, 5, and 6 are views of different forms of drag-bar holders. Fig. 7 is an enlarged view of the gearing, and Figs. 8 and 9 are detached views of the two forms of tooth-holders.

A represents the frame of the machine, it consisting, preferably, of a pipe bent into a U shape to form the sides 1 1 and the front 2. The grain-hopper, made of a pair of sloping sides 3 3 and metal end pieces 4 4, into which the sides are fitted and secured, is furnished with downwardly-projecting legs 5 5, which rest on and are rigidly secured to the rear ends of the sides 1 1 of the U-shaped frame. The axle 6 is loosely mounted in bearings 7 7, formed in the front legs 5 5, and the outer ends of the axle are supported in the hubs of the ground-wheels 8 8 in the usual manner. The tongue 9 is held fast to the frame A and

supported on the axle 6 by means of clip-plates 9 and 10, respectively, and the former is provided with a cap 11, on which are formed the depending ears 12 12, while the latter (plate 10) is connected with the seed-hopper, and thus partially supported by means of a strap 13. Corresponding with the depending ears 12 12, and performing the same function, are a series of different forms of drag-bar holders slightly modified to suit the different positions at which they are located on the frame. These different forms are shown in Figs. 4, 5, and 6, and as they are slightly different a detailed description will follow. The first, Fig. 4, consists of a clip-like piece of metal 14, bent to encircle the frame and open at one side, where perforated ears 15 15 are formed to receive a bolt, key, or other device by which the clip is drawn together or tightened upon the frame by the turning of a nut thereon or by upsetting the bolt or rivet. Inside a seat 16 is formed and adapted to enter a hole on the under side of the frame to prevent the cap or holder from turning thereon. A pair of depending ears 17 17, on the lower end of the holders, like the ears 12 12, receive the forward ends of the drag-bars 18 18. The second form, Fig. 5, of holder is provided with a screw-threaded socket 19 to receive the end of the brace-rod 20, which braces the tongue. There are generally two of these used, one on either side of the tongue. Otherwise this form is like the first one described. The third, Fig. 6, is like the first in its essential parts, but, being designed for attachment to the corner of the frame, the depending ears 17 17 are projected out laterally as well as downwardly, so as to lie parallel and in line with the other ears.

The drag-bars consist each of two narrow strips of metal separated a suitable distance apart at or near the middle by spacing-blocks 21 21, and spread apart at the forward end to span the distance between two holders, so that the adjacent ends of the strips composing the bars are pivoted between the ears of one holder. These drag-bars extend backward different distances, the alternate ones being short and long, so that the teeth are brought in two rows in the accustomed manner.

There are two forms of tooth-holders shown

in Figs. 8 and 9, and they will be described in order. In Fig. 8 it consists of a casting having a socket 22 in one side to receive the double diamond-pointed tooth 23 and a bolt-hole 24, which receives the bent bolt 25, which hooks over the tooth when it is in the socket, and is held in place by a nut or other device 26. A recess 27 is formed for the hook portion of the bolt to lie in when it is turned to one side to allow the tooth to enter the socket 22. A cap 28 is formed at the upper end of the casting to receive and form a closed sheath for the upper or unused point of the tooth and preserve it from wear or injury until the tooth is reversed. The casting or holder is provided with two elongated and slightly-curved slots 29 and 30, which extend about at right angles to each other. These are intended to receive the bolts by which the holders are adjustably and yieldingly held to the drag-bars. The slot 29 admits of its being pivoted at different inclinations to the drag-bar, while the slot 30 allows the holder to yield in case the tooth is struck by a stone or other obstruction. A spring or other device could be connected with the holder to insure its recoil into proper place after being struck. The other form (shown in Fig. 9) is substantially the same, but instead of having the two slots it merely has an opening to receive a bolt upon which it is supported, and it has a pair of internally-toothed parallel curved jaws 31 31. These have a link 32 inserted between them at different positions, and the forward end of each link is loosely connected with a vibrating lever 33, pivoted on the drag-bar, and the opposite end of the lever is pivotally connected with a spring-actuated slide-rod 34, which is loosely held at one end in a loop 35. By this means the teeth are made yielding, but they are made to regain their normal positions upon being released.

The axle 6 has mounted thereon several levers 36 36, the one on each side of the tongue of which are bell-crank levers. These levers are all adjustably secured in place by means of set-screws 37 37. The rods 38 38, pivoted to the drag-bars, extend loosely through the sockets 39 39, swiveled to the outer ends of these levers. Spiral springs 40 40, mounted loosely on the rods, keep them yieldingly depressed, and keys 41 41 hold them in the sockets.

The axle is oscillated by means of a compound lever. The main portion 43 of this lever is pivoted at its lower end to the rounded segment 43^a, which is vertically supported on the tongue. This segment is provided with a stop 44 on one side, which limits the forward movement of the lever, and with teeth 45 on its opposite face, with which the latch 46 engages. These teeth extend along only a portion of the segment and the balance is smooth, with a notch at the end to receive the latch. The outer rounded edge 47 forms a track upon which the toothed segment 48, se-

cured to lever 43, rides in its oscillations. A sleeve 49 is formed at one end of this segment 48 to receive the latch, and a spiral spring therein forces the latch outward. A secondary lever 50 is pivoted near the lower end of lever 43, and this lever also is furnished with a spring-actuated latch adapted to engage the teeth of the segment 48. The levers are both bent backward to bring the handles 51 at their ends within easy reach, and the usual means for operating the latches is provided. Connecting-rods 52 extend from the lower end of lever 50 to the bell-crank levers 36 36, and by this connection the axle is oscillated when one or both of the levers are swung. By means of the levers it is possible to sow the seed at a great variety of depths, as the distance raised or lowered by one-half of either lever is about one-half of the distance the teeth may be raised or lowered with a full sweep of both levers. To accomplish this with a single simple lever the sweep would necessarily be so great that the lever could not be handled.

The seed-hopper is braced through its middle by means of bracket-plate 53. This plate has flanges at its edges, by which it is secured to the sides of the hopper, and is ribbed to give it strength. A pair of truss-rods 54 54 extend from the ends of the hopper downward beneath this plate to give support to the hopper at the middle. The rods may be tightened by turning the nuts 55 55 on their ends. Several grain-cups 56 56 are secured to the bottom of the hopper, and to these the spouts for distributing the grain are removably secured. Either broadcast or drill spouts may be used. The force-feed wheels 57 57 are mounted on a shaft, whereby they may be shifted endwise through the cups to feed more or less grain, as required, and the guard-plates 58 58 limit the size of the discharge-opening for the grain. A pinion 59 is mounted on this shaft and adapted to turn the force-feed wheels at the required speed. A plate 60, having a collar 61, which is loosely mounted on a hub 62 on the end plate of the hopper, depends and carries a smaller hub 63 at its lower end, upon which a gear-wheel 64, which meshes with and drives pinion 59, turns. This gear-wheel is normally held in engagement with a similar wheel 60^a on the axle, which by means of a spring 65 and the gear-wheel 66 is rotated with one of the ground-wheels, with which it is connected. This spring 65 is secured to a lug on the plate 60 and bears against one of the legs of the hopper. A lug 67 on one of the legs limits the forward movement of the loosely-mounted plate. A short cam-lever 68 on the axle back of wheel 66 is adapted, when the teeth or hoes are raised from the ground, to bear against the plate 60, and by counteracting the effect of the spring force it back until the gear-wheels 59 and 66 are out of mesh. This stops the feed instantly. Guard-plate 70 is placed over this gearing.

It is evident that slight changes might be resorted to in the form and arrangement of the several parts described without departing from the spirit and scope of my invention, and hence I do not wish to limit myself to the particular construction herein set forth; but,

Having fully described my invention, what I claim as new, and desire to secure by Letters Patent, is—

10 1. In a seeding-machine, the combination, with a pipe-frame, of drag-bar holders mounted on the frame and having inwardly-projecting teats on their inner surfaces to enter holes in the frame for securing the holders against movement, and drag-bars pivoted to the holders, substantially as set forth.

2. In a seeding-machine, the combination, with a metal frame, of holders mounted thereon, the said holders being open at one side 20 and provided on their inner surfaces with inwardly-projecting teats adapted to enter holes in the frame, and bolts or similar devices for locking the holders on the frame.

3. The combination, with a frame, drag-bar 25 holders, and drag-bars pivoted thereto, of a lever carrying a lever, the latter being connected to the drag-bars, whereby they are raised or lowered, substantially as set forth.

4. The combination, with a frame and drag-bars 30 pivotally connected therewith, of a lever, a lever carried by said lever and having movement independent of the other lever, and means of connection between the lever and the drag-bars, substantially as set forth.

35 5. The combination, with a frame and drag-bars pivoted thereto, of a compound lever having connection with the drag-bars, one part of the lever being pivoted to the frame and having a toothed segment thereon and the 40 other part being pivoted to said portion and having a latch adapted to engage the teeth of the segment, substantially as set forth.

6. The combination, with a frame, tongue, and drag-bars pivoted to the frame, of a segment held on the tongue, said segment having a stop on one side, teeth on its opposite side, and a track on its edge, a lever pivoted to the segment and having a toothed segment which rides on the track, a second lever pivoted to the first lever and having a latch to engage the teeth on the segment, and means of connection between the levers and drag-bars, substantially as set forth.

7. The combination, with a frame and drag-bars 55 pivoted thereto, of a loosely-mounted axle, levers thereon having loose and yielding connection with the drag-bars, and a lever carried by a lever for imparting a part rotation to the axle, substantially as set forth.

60 8. The combination, with a frame and drag-bars pivoted thereto, of a loosely-mounted axle, levers adjustably secured to the axle and having loose and yielding connection with the drag-bars, a pivoted lever, and a lever pivoted 65 to said lever, and connecting-rod extending from the latter to the levers on the axle, substantially as set forth.

9. The combination, with a drag-bar, of a tooth-holder adjustably and yieldingly connected with the drag-bar and having a cap on 70 its upper end to receive the unused end of the tooth, substantially as set forth.

10. The combination, with a frame and a lever pivoted thereto, of drag-bars, a second lever mounted on a bearing carried by said first- 75 mentioned lever, devices for locking the second lever against independent movement, and devices connecting said second lever and the drag-bars, substantially as set forth.

11. The combination, with a frame, of a 80 grain-hopper supported thereon, said hopper having a bracket-plate therein, and truss-rods extending from the ends beneath the bracket-plate, substantially as set forth.

12. The combination, with a frame, of a 85 grain-hopper having metal ends, legs projecting downwardly therefrom and supported on the frame, a bracing-plate inside the hopper, truss-rods extending from the ends of the hopper beneath the bracing-plate, and means for 90 tightening the rods, substantially as set forth.

13. The combination, with a frame, drag-bars, hopper, and force-feed mechanism, of an oscillating axle, gearing for communicating motion therefrom to the feeding mechanism, 95 and means whereby the feeding is stopped simultaneously with the raising of the drag-bars, substantially as set forth.

14. The combination, with a frame, drag-bars, hopper, and feed mechanism, of an axle 100 having a gear-wheel loosely mounted thereon and a cam-lever fixed thereon, a gear-wheel on the feed mechanism, and a spring-actuated plate carrying a gear-wheel, which normally meshes with the wheel on the axle, but which 105 is thrown out of mesh by the cam-lever, substantially as set forth.

15. The combination, with the main frame, hopper, oscillating axle, drag-bars, tongue secured to the frame and connected with the 110 axle, and a compound lever for oscillating the axle, of feeding mechanism and gearing connected with the latter and the axle, whereby the feeding is stopped simultaneously with the rocking of the axle and raising of the 115 drag-bars, substantially as set forth.

16. The combination, with a frame and trussed hopper thereon, of a pole supported by the frame and hopper, substantially as set forth.

17. The combination, with the pipe-frame bent in U shape, of a trussed hopper supported on the frame and a pole secured to the frame and supported at its rear end by the trussed hopper, substantially as set forth.

In testimony whereof I have signed this specification in the presence of two subscribing witnesses.

WILLARD A. VAN BRUNT.
